UNITED STATES PATENT OFFICE.

VICTOR A. LANG, OF HOUSTON, TEXAS.

GAGE-COCK.

1,187,070.

Specification of Letters Patent. Patented June 13, 1916.

Application filed June 3, 1913. Serial No. 771,428.

To all whom it may concern:

Be it known that I, VICTOR A. LANG, a citizen of the United States, residing at Houston, in the county of Harris and State 5 of Texas, have invented certain new and useful Improvements in Gage-Cocks, of which the following is a specification.

This invention relates to new and useful improvements in gage cocks.

10 The object of the invention is to provide a device of the character described to be used in connection with the boiler of an engine for the purpose of determining the amount of water in said boiler and consists 15 of a simple, inexpensive and effective device designed to be used for the purpose indicated.

With the above and other objects in view, the invention has particular relation to certain 20 novel features of construction, operation and arrangement of parts, an example of which is given in this specification and illustrated in the accompanying drawings, wherein—

25 Figure 1 is a sectional side elevation of the device. Fig. 2 is a plan view of the connection by means of which the device is connected to a water column.

Referring now particularly to the drawings numeral 7 indicates a cylindrical casing, formed usually of brass and separated into two chambers 8 and 9 by means of the valve seat 10 having the diverging opening 11 therethrough. From the chamber 9 leads 35 the spout 12. The casing 7 is secured to the water column not shown by means of a connection 13, the outer end of which is threaded for engagement in a tapped hole through the wall of the water column and the inner 40 end of which has a reduced outwardly threaded nipple 14 upon which the casing 7 is screwed.

A valve stem 15 is provided upon which is fixed the valve 16, which conforms in 45 shape to and controls the passageway 11 of the seat 10. This valve stem slides through the bearings 17 and 17', the former of which is carried by the connection 13 and the latter of which is carried by the opposite end of 50 the casing 7.

Surrounding the valve stem and interposed between the connection 13 and the valve 16 is a coil spring 18 which normally holds the valve 16 firmly seated and prevents the escape of any steam or water 55 through the seat 10.

Pivoted to the outer end of the casing 7 is the lever 19 depending from which is the arm 20 which normally rests against the outer end of the valve stem 15. When it is 60 desired to open the valve 16, the lever 19 may be pressed downwardly which will impart an inward movement to the valve stem 15 through the arm 20 overcoming the pressure of the spring 18. Water, or steam, as 65 the case may be, is thus permitted to pass through the seat 10 and is discharged through the spout 12.

In actual use the operation of the device is as follows: a water level in a boiler may 70 be determined by a downward pressure on the lever 19. If when said lever is depressed steam is emitted from the spout 12, it will be apparent that the water level in the boiler is below the gage opening, and the amount 75 of water in the boiler can be quickly approximated.

What I claim is:

A device of the class described comprising a cylindrical casing having one end 80 open, its opposite outer end provided with a central opening, a wall formed interiorly of said casing intermediate its ends, a tapered valve seat centrally in said wall, a plug fitted in the open end of said casing, and 85 provided with a central opening in direct alinement with the tapered valve seat and the opening in the outer end, said wall dividing the casing into inner and outer compartments, a spout formed on the side wall 90 of said casing and communicating directly with the outer compartment, a valve stem slidable through the opening in the plug and extending out through the opening in the outer end of said casing, a valve formed 95 on said stem and adapted to engage the valve seat, a spring arranged around said stem one end engaging the inner face of the plug, its opposite end engaging the inner face of the valve and normally holding said 100

valve in engagement with the valve seat, and a lever pivotally connected to the outer end of said valve casing, an arm formed on said lever and extending laterally therefrom and adapted to engage the terminal end of the valve stem for unseating said valve.

5 In testimony whereof I have signed my

name to this specification in the presence of two subscribing witnesses.

VICTOR A. LANG.
